CLAIM

The ornamental design for a multi-tier shelf assembly, as shown and described.

DESCRIPTION

FIG. 1 is a top perspective view of a multi-tier shelf assembly;

FIG. 2 is a top perspective view thereof;

FIG. 3 is a bottom perspective view thereof;

FIG. 4 is a bottom perspective view thereof;

FIG. 5 is a front elevational view thereof;

FIG. 6 is a right-side elevational view thereof;

FIG. 7 is a top plan view thereof; and,

FIG. 8 is a bottom plan view thereof.

The broken lines in the drawings form no part of the claimed design. A rear elevational view is not shown because it is identical to the front elevational view shown in FIG. 5. A left-side elevational view is not shown because it is identical to the right-side elevational view shown in FIG. 6. The broken lines showing the additional shelves is for the purpose of illustrating environmental structure and forms no part of the claimed design.
